CONVECTOR CABINET

James Teague, Chicago, Ill., assignor to Modine
Manufacturing Company, Racine, Wis., a cor-
poration of Wisconsin

Application February 11, 1949, Serial No. 806

Term of patent 14 years

(Cl. D81—21)

To all whom it may concern:

Be it known that I, James Teague, a citizen of the United States, residing at Chicago, in the county of Cook and State of Illinois, have invented a new, original, and ornamental Design for a Convector Cabinet, of which the following is a specification, reference being had to the accompanying drawing, forming part thereof.

In the drawing:

Fig. 1 is a perspective view of a convector cabinet embodying my new design, with the grill member in open position; and

Fig. 2 is a perspective view of the cabinet illustrated in Fig. 1 with the grill member in closed position.

The characteristic feature of the convector cabinet disclosed resides in the configuration of the tilted grille, as best shown in Fig. 1.

The end of the cabinet not visible in the drawings is the same shape as the end illustrated.

I claim:

The ornamental design for a convector cab-
inet, as shown and described.

JAMES TEAGUE.
